LASTING MACHINE

Bernhardt Jorgensen, Marblehead, Mass., assignor to United Shoe Machinery Corporation, Flemington, N. J., a corporation of New Jersey

Application February 15, 1943, Serial No. 475,857

28 Claims. (Cl. 12—14)

This invention relates to lasting machines, and more particularly to machines for lasting the sides of the foreparts of shoes beyond their toe portions, including especially their ball portions. An immediate object of the invention is to provide improvements in a machine such as disclosed in an earlier application of mine, Serial No. 466,746, filed on November 24, 1942, and the invention is accordingly herein illustrated as embodied in a modification of that machine, but it should be understood that it is not thus limited in its applicability.

The machine shown in the above-mentioned application is particularly adapted for lasting the sides of the foreparts of shoes of that kind in which the margin of the upper in those locations is lasted over an insole in parallel relation to the bottom of the last and is fastened to the insole by cement. For that purpose the machine is provided with wipers carried by arms which are moved about axes extending heightwise of the shoe, the wipers comprising thin steel plates which are resiliently flexible in directions heightwise of the shoe for better conformity to the contour of the bottom of the shoe in response to increased pressure of the shoe against them when they are over the shoe bottom. Associated with the wipers are retarders which in response to the operative inward movements of the wiper-carrying arms are moved outwardly over the insole toward the wipers into positions to clamp the margin of the upper against the edges of the wipers, the retarders preventing the margin of the upper from adhering prematurely to the insole and insuring also that the margin of the insole is properly positioned on the bottom of the last. The retarders cooperate with the wipers to pull the margin of the upper inwardly over the extreme edge of the insole, whereupon they are moved heightwise of the shoe out of the paths of the wipers by the movements of the wiper-carrying arms and are then moved outwardly over the wipers as the latter continue their inward wiping movements.

An object of this invention is to improve results in the operation of such a machine on portions of a shoe where the edge of the shoe bottom curves inward heelwardly of the ball line, especially when such curvature is pronounced and when the previous lasting of the shank portion of the shoe has terminated at a substantial distance from the ball line. To this and other ends, the machine herein shown is provided with additional wipers movable inwardly between the shoe and the wiping faces of the

above-mentioned wipers (which for purposes of designation may be termed the main wipers), the additional wipers wiping the margin of the upper over the insole in locations where the edge of the shoe bottom curves inward heelwardly of the ball line and having components of movement toward the toe end of the shoe along the wiping faces of the main wipers. The additional wipers thus wipe the margin of the upper inwardly in directions substantially perpendicular to the inwardly curved portions of the edge of the insole, which is desirable for the best results in the lasting operation. Further to insure the proper lasting of the portions of the upper on which the machine operates, provision is afforded for the additional wipers to begin their lasting operations on the upper earlier than the main wipers, the construction shown being also such that they terminate their inward wiping movements after the beginning but prior to the termination of the wiping action of the main wipers on the upper. The additional wipers, in the construction shown, comprise thin steel plates which are flexible like the main wipers, and as further herein illustrated they are carried by arms which are swung about axes extending heightwise of the shoe and are operated by the arms which carry the main wipers.

The invention further provides additional retarders arranged to cooperate with the additional wipers, these additional retarders, in the construction shown, being moved outwardly over the insole in different directions than the retarders associated with the main wipers, with components of movement away from the toe end of the shoe, in view of the directions of movement of the additional wipers. For this purpose they are carried by arms mounted to swing about axes extending heightwise of the shoe in the appropriate locations, these arms being operated by the same means whereby outward movements are imparted to the retarders associated with the main wipers. As illustrated, the additional retarders are forced heightwise of the shoe away from the insole by pressure of the margin of the upper against them, whereupon they are moved farther outwardly over the additional wipers in the course of the wiping operation.

50 The above and other features of the invention, including various novel details of construction and combinations of parts, will now be more particularly described with reference to the accompanying drawings and thereafter pointed out in the claims.

In the drawings,

Fig. 1 is a view in right-hand side elevation of the machine in which the invention is herein shown as embodied, portions of the structure being broken away and the parts being shown in their starting positions;

Fig. 2 is a plan view of the machine with the parts in their starting positions, the position of a shoe in the machine being indicated diagrammatically by broken lines;

Fig. 3 is a plan view of a portion of the structure shown in Fig. 2, with the parts in the positions which they occupy just as the additional wipers begin to wipe the margin of the upper inwardly over the insole;

Fig. 4 is a plan view similar to Fig. 2, but showing the parts as they appear when all the wipers have completed their inward wiping movements;

Fig. 5 is a section on the line V—V of Fig. 3, showing the parts in the same positions as in Fig. 3; and

Figs. 6 and 7 are vertical sectional views showing one of the main wipers and parts associated therewith as they appear at certain times in the operation of the machine.

Like the machine shown in the previously mentioned application, the machine herein shown is provided with a column 2 terminating at its upper end in a horizontal shelf 4 on which are secured the lower ends of two vertical frame plates 6 spaced apart widthwise of the machine and integral at their upper ends with a horizontal top plate 8. Pivotedly mounted substantially midway between its opposite ends on a bifurcated member 10 fast on this top plate is a forwardly and rearwardly extending lever 12 provided at its front end with a hold-down member 14 (Fig. 2) arranged to engage the bottom of the forepart of the shoe to determine the position of the shoe heightwise and with respect to tipping movements about axes extending lengthwise and laterally thereof. The position of the shoe lengthwise is determined as hereinafter described, the end gage provided for that purpose in the earlier construction being omitted. Its position widthwise is determined by a pair of side gages 16 (Fig. 4) arranged to contact with the opposite sides of its ball portion, these gages being secured to upwardly extending arms of bell-crank levers 18. The bell-crank levers are pivotally supported on an arm 20 (Fig. 1) extending forwardly from a plate 22 which is part of a vertical cylinder 24 mounted on the shelf 4 between the frame plates 6 for a purpose hereinafter described, and they are adjustable by means of a screw 26 to vary the distance between the two side gages 16, as more fully disclosed in the previously mentioned application.

After the shoe has been presented by the operator bottom upward under the hold-down 14 and between the side gages 16, it is clamped against the hold-down by a shoe rest 28 which engages the top of its forepart. The shoe rest is supported on an arm 30 fast on a rockshaft 32 mounted on the frame plates 6, and also fast on one end of this rockshaft is another arm 34 connected to a treadle 36 by depression of which the operator moves the shoe rest upwardly into engagement with the shoe. The connections between the treadle and the arm 34 include a rod 38 connected by a turnbuckle 40 to another rod 42 slidably movable in a block 44 which is pivotally mounted on the rear end of the arm 34, and further include a spring 46 mounted between

a collar 48 resting on the block 44 and a collar 50 held by a nut 52 on the rod 42. Accordingly the spring 46 is yieldable in response to further depression of the treadle 36 after the shoe rest 28 has been moved into position to clamp and hold the shoe.

For wiping the margin of the upper inwardly over the insole at the opposite sides of the ball portion of the shoe the machine is provided as

10 heretofore with a pair of comparatively thin steel wipers 54 resiliently flexible in directions heightwise of the shoe and each secured by a pair of bolts 56 (Fig. 2) to a forwardly extending arm 58 of a bell-crank lever 60 pivotally mounted

15 on a stud 62 on the top plate 8 to swing about an axis extending heightwise of the shoe. The two bell-crank levers 60 have other arms 64 extending widthwise of the shoe in crossed relation to each other and connected by links 66 to upwardly extending arms 68 of other bell-crank

20 levers 70 mounted on a rod 72 to swing about an axis extending widthwise of the shoe, this rod being supported on an arm 74 extending rearwardly from the previously mentioned plate 22.

25 Forwardly extending arms 76 of the bell-crank levers 70 are connected by links 78 to a rod 80 which extends through vertical slots 82 in the sides of the previously mentioned cylinder 24 and through a piston 84 in the cylinder. In response to upward movement of this piston, therefore, wiper-operating movements are imparted through the bell-crank levers 70 to the bell-crank levers 60, the wiper-carrying arms 58 of the latter being swung inwardly toward each other.

30 Such upward movement of the piston 84 is effected by operating fluid, which may be compressed air, admitted to the lower end of the cylinder 24. For this purpose the cylinder is connected by a conduit 86 to valve mechanism 88

40 which controls the admission and exhaust of air to and from the cylinder. The valve mechanism comprises a tube 90 clamped between two blocks 92 and 94 fast on an inclined arm 96 extending rearwardly from the shelf 4. One end of the tube

45 90 is in communication through a passageway in the block 92 with the conduit 86, and the other end of the tube is in communication with a conduit 98 leading from a suitable source of compressed air supply. Midway of its length the tube 90 has a partition 100 extending across it, and extending through the walls of the tube at the opposite sides of this partition, respectively, are ports 102 and 104. Movable along the tube is a sleeve valve 106 provided with an annular

50 chamber 108 which, when the valve is in one position, provides communication between the ports 102 and 104 and thus admits compressed air to the cylinder 24. When the valve is in the position shown in Fig. 1 the ports 102 are open to the atmosphere and the piston 84 is at the lower end of the cylinder, in which position it is maintained by springs 110 connected to the arms 76. Movement of the valve into position to admit compressed air to the cylinder is effected by further movement of the treadle 36 after the shoe rest 28 has been moved into shoe-clamping position.

55 For this purpose an arm 112 is pivotally mounted at 114 on the supporting arm 96 and is provided with a pin 116 extending into a groove in the valve 106. The valve is maintained normally in its initial position, determined by its engagement with the block 94 as shown in Fig. 1, by a spring 118 connected to a pin 120 on the arm 112. This pin extends through a slot 122 in an inclined link 124 pivotally connected at its lower

end to a collar 126 fast on the treadle-operated rod 38. When this rod is moved downwardly, therefore, downward movement is imparted to the link 124, but by reason of the slot 122 in the link no movement is imparted to the valve-operating arm 112 until after the shoe rest 28 has been moved into clamping position. Further movement of the treadle thereafter against the resistance of the spring 46 serves to move the valve 106 into position to admit compressed air to the cylinder 24 and thus to cause the wipers 54 to be operated. When the treadle is released by the operator after the operation of the machine on a shoe, it is raised by a spring 128 connected to a collar 130 fast on the rod 38, and by the action of this spring return movement is imparted to the link 124. This permits the valve 106 to be moved by the spring 118 into position to open the ports 102 to the atmosphere and thus to permit exhaust of the air from the cylinder 24, the wipers being returned to their initial positions by the action of the springs 119. Return movement of the treadle is limited by engagement of a screw 132 (Fig. 2) threaded in an arm 134 fast on one end of the shaft 32 with a lug 136 on one of the frame plates 6.

When a shoe is pressed upwardly against the holdown 14 by the shoe rest 28, movement of the lever 12 by the pressure of the shoe on the holdown is prevented by an arm 138 mounted to swing about the rod 12 and provided with a roll 140 which underlies the rear end of the lever. A spring 142 connected to the arm holds it normally in an upright position determined by engagement of the roll 140 with a lug 144 on the lever. When the wipers 54 have substantially or nearly completed their inward wiping movements the arm 138 is swung rearwardly to release the lever 12 and thus to permit the shoe to be pressed more forcibly up against the wipers by the shoe rest 28 under control of the spring 46, thus insuring that all portions of the margin of the upper wiped inwardly by the wipers will be pressed firmly down on the insole. To effect such swinging movement of the arm 138 the upwardly extending arms 68 of the bell-crank levers 70 carry a yoke member 146 provided with a screw 148 arranged to engage the arm 138, the screw being adjustable to determine the time with respect to the operative movements of the wipers when their pressure on the upper is increased. The initial position of the lever 12 is determined by a stop 150 on the top plate 8, against which the front arm of the lever is held by a light spring 152.

The bolts 56 which secure the flexible wipers 54 to the arms 58 are located substantial distances widthwise of the shoe from the shoe-engaging portions of the wipers, and accordingly these portions of the wipers are left free throughout their lengths to be flexed or bent by the increased upward pressure of the shoe against them when the lever 12 is released as above described. This permits the wipers to conform satisfactorily to the more or less convex lengthwise and lateral curvatures of the bottom of the ball portion of the shoe and thus to apply adequate pressure to all portions of the margin of the upper on which they act. The arms 58, however, carry screws 154 and 156 arranged to engage the top faces of the wipers at their front and rear ends, respectively, to limit the bending of the shoe-engaging portions of the wipers as a whole, and the support which the screws thus afford for the front and rear ends of the wipers after they engage them contributes to such further bend-

ing of the portions of the wipers between the screws as to conform properly to the lengthwise curvature of the bottom of the ball portion of the shoe. The wiper-carrying arms 58 are braced against upward deflection by the pressure of the shoe on the wipers by means of blocks 158 fast on the top plate 8 and under portions of which the arms are moved in operating the wipers, these blocks having shoulders 160 which by engagement with the arms limit the operative movements of the wipers. The wipers are maintained in a heated condition, as is preferable in lasting with cement, by electrical heating units 162 mounted in blocks 164 secured to the lower faces of the wipers. The studs 62 about which the wipers are swung are at such a distance apart that the wipers have small components of movement lengthwise of the shoe toward its toe end as they are moved inwardly widthwise of the shoe.

Arranged to cooperate with the wipers 54 to control the margin of the upper as it is wiped inwardly over the insole are retarders 166 which press or clamp the margin of the upper in upward standing position against the edges of the wipers prior to and at the beginning of the wiping operation and also serve to press the margin of the insole down on the bottom of the last. These retarders extend substantial distances lengthwise of the shoe and are curved laterally of the shoe similarly to the corresponding portions of the edges of the wipers. They are supported by carrier arms 168 mounted on studs 170 on the top plate 8 to swing toward and from each other widthwise of the shoe. A spring 172 connected to the arms 168 tends to swing them toward each other and holds them initially in positions determined by engagement of the retarders with the holdown 14, from which positions the arms are swung outwardly to carry the retarders toward the side edges of the insole and toward the wipers by means herein-after described. Each retarder has an offset upwardly extending cylindrical portion 174 (Fig. 6) mounted in a socket in the arm 168 and engaged by a spring 176 which tends to move the retarder downwardly, the limit of its downward movement being determined by a collar 178 fast on a stem 180 extending upwardly from the cylindrical portion 174, the collar normally engaging the top of the arm 168. Initially the retarders 166 extend downwardly short distances beyond the holdown 14, and they are moved upwardly against the resistance of the springs 176 by pressure of the shoe thereon when the shoe is pressed upwardly against the holdown by the shoe rest 28. Insurance is thus afforded that the retarders will press the insole down on the bottom of the last when they are moved outwardly toward the wipers. Connected to pins on the collars 178 are springs 182 which initially hold the retarders in definite positions with respect to turning movements about the axes of the stems 180 but permit them to turn and adjust themselves to the wipers when the upper is pressed against them by the wipers. For swinging the arms 168 outwardly to carry the retarders toward the side edges of the insole there are provided other arms 184 (Figs. 1 and 2) mounted on studs 186 on the plate 8 to swing widthwise of the shoe and connected to the arms 168 by links 188. Also mounted to swing about the studs 186 are plates 190. Each of these plates is held at all times in predetermined

adjusted relation to the arm 184 associated therewith by means including an adjusting screw 192, as fully disclosed in the previously mentioned application. Each plate is provided with a projection 194 arranged to be engaged by a finger 196 formed on or secured to the adjacent wiper-carrying arm 58. When the two arms 58, therefore, are swung inwardly to operate the wipers the fingers 196 have a cam-like action on the plates 190 to swing these plates and the arms 184 as units in outward directions, thus swinging the retarder-carrying arms 168 outwardly against the resistance of the spring 172. In this manner the retarders 166 are moved outwardly over the insole toward the wipers as the wipers are being moved inwardly toward the side edges of the insole, the retarders serving to spread from over the insole any portion of the margin of the upper which may extend inwardly over it. At the time when the outwardly moving retarders and the inwardly moving wipers arrive in positions to clamp the upstanding margin of the upper between them, the retarders preferably are so located that their upper-engaging faces are positioned slightly farther outward than the side edges of the insole, so as to detach from the edges of the insole any portion of the upper which may have adhered prematurely thereto. In order that the retarders may thus be properly positioned relatively to the side edges of the insole in operating on shoes of different widths, the plates 190 are adjustable about the studs 198 relatively to the arms 184 by the screws 192. In this manner the time in the movements of the arms 58 when their fingers 196 begin to swing the arms 184 and the retarders outwardly may be varied to vary the distances the retarders are thus moved before the upper is first clamped against them by the wipers.

Each of the links 188 is mounted to swing in directions heightwise of the shoe about a stud 198 on the end of the arm 184 associated therewith, the main portion of the link being also so mounted as to permit it to swing in directions lengthwise of the shoe about a pin 200 relatively to the portion thereof which is mounted on the stud 198. The inner end portion of the link (Fig. 6) is so shaped as to extend downwardly and then inwardly under the cylindrical portion 174 of the retarder 166, the inner end of the link being provided with a slot 202 through which a headed stud 204 extends downwardly from the cylindrical portion 174. A spring 206 connected to the link 188 and to the arm 168 tends to swing the arm outward relatively to the link and holds it normally in a relation to the link determined by engagement of the stud 204 with the link at the outer end of the slot 202. As the wipers continue their inward movements from the positions where they first clamp the upper against the retarders 166 they force the retarders inwardly against the resistance of the springs 206, the studs 204 being moved inwardly along the slots 202. In this manner the wipers and the retarders cooperate to apply an inward pull to the margin of the upper over the extreme edge of the insole. Shortly after the wipers begin to wipe the margin of the upper inwardly, however, the retarders are lifted against the resistance of the springs 176 to withdraw them from the paths of the wipers. For this purpose the links 188 have adjustably supported thereon rolls 208 (Fig. 6) which are engaged by the wiper-carrying arms 58 to swing the links upwardly

about the studs 198 and thereby to lift the retarders. When the retarders have thus been lifted they are moved outwardly over the wipers by contraction of the springs 206 and by the continued swinging movements of the arms 184. At the beginning of such outward movements of the retarders over the wipers they bend the margin of the upper outwardly and thus increase the effectiveness of the wipers in wiping the upper tightly and smoothly over the insole.

As thus far described, the machine herein shown may be assumed to be constructed substantially as disclosed in the previously mentioned application. For purposes of this invention there are provided additional wipers 210 for wiping the margin of the upper inwardly over the insole in locations where the edge of the shoe bottom curves inward heelwardly of the ball line. These wipers comprise thin steel plates 210 resiliently flexible like the wipers 54 and arranged to be moved inwardly over the shoe bottom between the shoe and the wipers 54 in contact with the wiping faces of the latter. The wipers 210 are fast on forwardly extending arms 212 of levers 214 mounted to swing about the axes of vertical pins 216 to which they are secured and which are rotatable in bearings in brackets 218 on the frame plates 6. Swinging movements are imparted to the levers 214 to operate the wipers 210 by the movements of the arms 58 which carry the wipers 54. For this purpose the arms 58 are connected to the forwardly extending arms 212 of the levers 214 by links 220 pivotally connected at their inner ends to the arms 58 and slidably movable in blocks 222 pivoted on the arms 212. Between these blocks and nuts 224 on the outer ends of the links are springs 226 which are yieldable to permit further inward swinging movements of the arms 58 after movements of the levers 214 have been stopped as hereinafter described. Nuts 228 on the links serve by engagement with the blocks 222 to impart return movements to the levers 214. As the wipers 210 are thus operated they have substantial components of movement lengthwise of the shoe toward its toe end along the wiping faces of the wipers 54 by reason of the locations of the pins 216, which are farther apart widthwise of the shoe than the studs 62 about which the arms 58 are swung, and by reason of the shape of the arms 212 which are curved inwardly toward each other widthwise of the shoe. The wipers 210, therefore, wipe the margin of the upper inwardly over the inwardly curved portions of the edge of the insole extending heelwardly of the ball line in directions substantially perpendicular to these portions of the edge of the insole, as is desirable for satisfactory results in the lasting operation. The wipers 210 are heated by their contact with the heated wipers 54, and they may bend with the wipers 54 to conform better to the contour of the shoe on all the wipers is increased in the manner hereinbefore described. The arrangement of the links 220 relatively to the arms 58 and the arms 212 is such that the wipers 210 are moved inward more rapidly than the wipers 54 and begin to act on the upper earlier than the wipers 54, as is desirable in operating on portions of the upper extending heelwardly of the ball line. To prevent the wipers 210 from being moved too far inwardly over the shoe bottom and too far toward the toe end of the shoe relatively to the wipers 54, the machine is provided with

means for stopping their inward movements prior to the completion of the inward movements of the wipers 54. For this purpose each of the brackets 218 has thereon an outwardly extending rod 230 on which is threaded a nut 232 arranged to be engaged by the bifurcated rear end of a rearwardly extending arm 234 of the lever 214. It will be understood that by adjustment of the nuts 232 the limits of the inward movements of the wipers 210 may be varied each independently of the other.

Arranged to cooperate with the additional wipers 210 are additional retarders 236 which clamp the margin of the upper against the edges of these wipers, these retarders also pressing corresponding portions of the margin of the insole down on the bottom of the last. The retarders 236 are carried by arms 238 mounted to swing about the previously mentioned studs 186 about which also swing the arms 184 and the plates 190 whereby outward movements are imparted to the retarders 166 associated with the wipers 54. The retarders 236 are provided with stems 240 extending upwardly through the arms 238 and having fast on their upper ends collars 242 for limiting downward movements of the retarders. Springs 244 connected to these collars hold the retarders 236 normally in predetermined positions with respect to turning movements about the axes of the stems 240 but permit them to turn in such manner as to adjust themselves to the edges of the wipers against which they clamp the margin of the upper. The arms 238 are swung to carry the retarders 236 outwardly over the insole into positions to clamp the upper against the wipers 210 by the outward swinging movements of the plates 190 and the arms 184. For this purpose these plates have pins 246 extending upwardly into slots in the arms 238 and engaged by springs 248 in the arms. When, therefore, the outward swinging movements are imparted to the arms 184 corresponding movements also are imparted to the arms 238 through the springs 248. By reason of the locations of the studs 186, the retarders 236 are swung outwardly with components of movement lengthwise of the shoe away from its toe end, as is appropriate in view of the directions of movement of the wipers 210. To return the arms 238 to their initial positions the pins 246 act on screws 250 which are threaded in the arms and are engaged by the pins, the arms being adjustable about the studs 186 by means of these screws. When the retarders 236 first clamp the margin of the upper against the wipers 210 the retarders are positioned substantially at the edge of the insole. The retarders, however, are provided with inclined upper-engaging faces (Fig. 5), and they are movable upwardly against the resistance of springs 252 in the arms 238 in response to the pressure of the upper against these faces as the wipers begin to wipe the upper inwardly over the insole. In this manner the retarders are forced heightwise of the shoe out of the paths of the wipers, whereupon they are moved farther outwardly over the wipers by continued outward movements of the arms 238, bending the margin of the upper outwardly over the edges of the wipers to render the wipers more effective in wiping the upper tightly inward over the insole. The outward swinging movements of the arms 238 are limited by stop screws 254 threaded in the brackets 218 and arranged to be engaged by lugs 256 on the arms, in order to avoid interference between the retarders 236 and other parts of the

5 machine. It will be understood that when the movements of the arms 238 are thus stopped the springs 248 are yieldable to permit continued outward movements of the arms 184 which control the retarders 166.

In the use of the machine the operator presents a shoe between the side gages 16 with the bottom of its forepart against the retarders 166 and 236. When the shoe is thus presented the retarders 236 are conveniently utilized to indicate the proper position of the shoe lengthwise, the shoe, however, being so positioned by the operator that these retarders are located at some distances inwardly from the portions of the edge of the insole over which the margin of the upper is to be wiped by the corresponding wipers 210. After thus presenting the shoe the operator by depression of the treadle 36 swings the shoe rest 28 upwardly and thereby forces the shoe upwardly against the holdown 14, lifting the several retarders a short distance against the resistance of their controlling springs 176 and 252. Further depression of the treadle then serves to compress the spring 46 and to move the valve 106 into position to admit compressed air to the cylinder 24. By the action of the piston 84 the wiper-carrying arms 58 are then operated to impart inward movements to the wipers 54, and through the link connections 220 between these arms and the arms 212 the latter also are operated to impart inward movements to the additional wipers 210. As hereinbefore explained, and as illustrated in Fig. 3, these wipers arrive in positions to begin to wipe the margin of the upper over the inwardly curved portions of the edge of the insole extending heelwardly of the ball line before the wipers 54 arrive in positions to begin their wiping action on the upper, and they terminate their inward wiping movements by reason of engagement of the arms 234 with the stop nuts 232 after the beginning but prior to the completion of the wiping action of the wipers 54 on the upper, the springs 226 yielding to permit the latter wipers to complete their movements. As the several wipers are thus moved inwardly the fingers 196 on the wiper-carrying arms 58 have a cam-like action on the projections 194 of the plates 190 to impart outward swinging movements to these plates and the arms 184, these arms acting 60 through the links 188 to move the retarders 166 outwardly over the insole toward the wipers 54. At the same time outward swinging movements are imparted to the arms 238 to carry the retarders 236 outwardly over the insole toward the wipers 210, these arms being operated by the plates 190 through the pins 246 and the springs 248. It will be understood that the several retarders serve to spread from over the insole any portion of the margin of the upper which may 65 extend inwardly over it and thereafter to clamp or press the margin of the upper against the edges of the corresponding wipers to prevent it from adhering prematurely to the insole and to render the wipers more effective to last the upper tightly and smoothly over the last and the insole. Additionally they serve to insure that the margin of the insole is properly positioned on the bottom of the last when the upper is wiped over it by the wipers. The retarders 236 arrive in positions to clamp the upper against the wipers 210 substantially at the edge of the insole before the retarders 166 arrive in a corresponding relation to the wipers 54, and as the wipers 210 continue their inward movements the retarders 236 are 70 forced upwardly by the pressure of the margin of

the upper on their inclined faces, as illustrated in Fig. 5. When these retarders have been forced upwardly far enough to clear the wipers they are carried outwardly over them by the arms 238, bending the margin of the upper outwardly over the edges of the wipers as they begin their outward movements over them. Such outward movements of the retarders 236 are limited by engagement of the lugs 256 on the arms 238 with the stop screws 254 (Fig. 4). Shortly after the wipers 210 begin to wipe the margin of the upper over the insole the retarders 166 arrive in positions to clamp the margin of the upper against the edges of the inwardly moving wipers 54 substantially at the edge of the insole. Thereafter the retarders 166 cooperate with the wipers 54 to apply an inward pull to the margin of the upper over the extreme edge of the insole (Fig. 6), whereupon they are lifted clear of the paths of the wipers by the action of the arms 58 on the rolls 208 and are then moved outwardly over the wipers by continued outward swinging movements of the arms 184, as more fully disclosed in the previously mentioned application. As they begin to move outwardly over the wipers they bend the margin of the upper over the edges of the wipers, as illustrated in Fig. 7. Near the end of the inward wiping movements of the wipers 54 the hold-down-supporting lever 42 is released by the arm 138, thus permitting the spring 46 by its action on the shoe rest 28 to force the shoe more firmly up against the several wipers which may bend to conform better to the contour of the shoe bottom. The operator preferably holds the treadle depressed long enough to cause the heated wipers to continue for a few seconds their pressure on the overwiped margin of the upper, thus allowing more time for the cement to set while the upper is pressed smoothly on the insole. The operator then releases the treadle, whereupon the various parts are returned to their starting positions by reason of the release of the compressed air from the cylinder 24.

Having described the invention, what I claim as new and desire to secure by Letters Patent of the United States is:

1. In a lasting machine, wipers movable to wipe the margin of an upper inwardly over an insole at the opposite sides of the forepart of a shoe beyond its toe portion, and additional wipers movable inwardly in contact with the wiping faces of said first-named wipers with components of movement along said faces toward the toe end of the shoe to wipe the margin of the upper over the insole in locations where the edge of the shoe bottom curves inward heelwardly of the ball line.

2. In a lasting machine, wipers movable to wipe the margin of an upper inwardly over an insole at the opposite sides of the ball portion of a shoe, additional wipers movable inwardly between the shoe and the wiping faces of said first-named wipers with components of movement along said faces toward the toe end of the shoe to wipe the margin of the upper over the insole in locations where the edge of the shoe bottom curves inward heelwardly of the ball line, and means for thus moving said additional wipers in automatically determined time relation to the operative movements of said first-named wipers.

3. In a lasting machine, wipers movable to wipe the margin of an upper inwardly over an insole at the opposite sides of the forepart of a shoe beyond its toe portion, additional wipers movable inwardly in different directions than said first-named wipers between the latter and

the bottom of the shoe with components of movement toward the toe end of the shoe to wipe the margin of the upper over the insole in locations where the edge of the shoe bottom curves inward heelwardly of the ball line, and means to cause said additional wipers to begin their wiping action on the upper earlier than said first-named wipers and to continue their inward wiping movements thereafter when the first-named wipers also are in wiping contact with the upper.

4. In a lasting machine, wipers movable to wipe the margin of an upper inwardly over an insole at the opposite sides of the forepart of a shoe beyond its toe portion, additional wipers movable inwardly in different directions than said first-named wipers between the latter and the bottom of the shoe with components of movement toward the toe end of the shoe to wipe the margin of the upper over the insole in locations where the edge of the shoe bottom curves inward heelwardly of the ball line, and means to cause said additional wipers to begin their wiping action on the upper earlier than said first-named wipers and to terminate their inward wiping movements after the beginning but prior to the termination of the wiping action of said first-named wipers on the upper.

5. In a lasting machine, wipers movable to wipe the margin of an upper inwardly over an insole at the opposite sides of the ball portion of a shoe, additional wipers movable inwardly over the shoe bottom in different directions than said first-named wipers with components of movement toward the toe end of the shoe to wipe the margin of the upper over the insole in locations where the edge of the shoe bottom curves inward heelwardly of the ball line, and means to cause said additional wipers to begin their wiping action on the upper earlier than said first-named wipers and to terminate their inward wiping movements after the beginning but prior to the termination of the wiping action of said first-named wipers on the upper.

6. In a lasting machine, wipers movable to wipe the margin of an upper inwardly over an insole at the opposite sides of the ball portion of a shoe, additional wipers movable inwardly over the shoe bottom in different directions than said first-named wipers with components of movement toward the toe end of the shoe to wipe the margin of the upper over the insole in locations where the edge of the shoe bottom curves inward heelwardly of the ball line, and power-operated means for imparting operative movements simultaneously to all said wipers, said additional wipers being arranged to begin their wiping action on the upper earlier than said first-named wipers.

7. In a lasting machine, wipers movable to wipe the margin of an upper inwardly over an insole at the opposite sides of the ball portion of a shoe, additional wipers movable inwardly over the shoe bottom in different directions than said first-named wipers with components of movement toward the toe end of the shoe to wipe the margin of the upper over the insole in locations where the edge of the shoe bottom curves inward heelwardly of the ball line, and power-operated means for operating all said wipers in such relation to one another as to cause said additional wipers to begin their wiping action on the upper earlier than said first-named wipers and to terminate their inward wiping movements after the beginning but prior to the termination of the wiping action of said first-named wipers on the upper.

8. In a lasting machine, wipers movable to wipe the margin of an upper inwardly over an insole at the opposite sides of the ball portion of a shoe, additional wipers movable inwardly over the shoe bottom in different directions than said first-named wipers with components of movement toward the toe end of the shoe to wipe the margin of the upper over the insole in locations where the edge of the shoe bottom curves inward heelwardly of the ball line, means common to all said wipers for operating them, and stop mechanism for limiting the operative movements of said additional wipers independently of the movements of said first-named wipers.

9. In a lasting machine, wipers movable to wipe the margin of an upper inwardly over an insole at the opposite sides of the ball portion of a shoe, additional wipers movable inwardly over the shoe bottom in different directions than said first-named wipers with components of movement toward the toe end of the shoe to wipe the margin of the upper over the insole in locations where the edge of the shoe bottom curves inward heelwardly of the ball line, means common to all said wipers for operating them, and stops associated respectively with said additional wipers for adjustably limiting the operative movement of each of them independently of the movement of the other and independently of the movements of said first-named wipers.

10. In a lasting machine, wipers movable to wipe the margin of an upper inwardly over an insole at the opposite sides of the forepart of a shoe beyond its toe portion, supports for said wipers movable thus to operate them, additional wipers movable inwardly over the shoe bottom in different directions than said first-named wipers with components of movement toward the toe end of the shoe to wipe the margin of the upper over the insole in locations where the edge of the shoe bottom curves inward heelwardly of the ball line, supports for said additional wipers movably mounted independently of said first-named wiper supports, and means for operating the supports for said additional wipers by the movements of said first-named supports.

11. In a lasting machine, wipers movable to wipe the margin of an upper inwardly over an insole at the opposite sides of the forepart of a shoe beyond its toe portion, supports for said wipers movable thus to operate them, additional wipers movable inwardly over the shoe bottom in different directions than said first-named wipers with components of movement toward the toe end of the shoe to wipe the margin of the upper over the insole in locations where the edge of the shoe bottom curves inward heelwardly of the ball line, supports for said additional wipers movably mounted independently of said first-named wiper supports, yieldable means for operating the supports for said additional wipers by the movements of said first-named supports, and stop mechanism for limiting the operative movements of the additional wipers independently of the movements of said first-named wipers.

12. In a lasting machine, wipers movable to wipe the margin of an upper inwardly over an insole at the opposite sides of the forepart of a shoe beyond its toe portion, arms supporting said wipers and mounted to swing each about an axis extending heightwise of the shoe thus to operate the wipers, additional wipers movable inwardly over the shoe bottom in different directions than said first-named wipers with components of movement toward the toe end of the shoe to wipe

the margin of the upper over the insole in locations where the edge of the shoe bottom curves inward heelwardly of the ball line, arms supporting said additional wipers and mounted to swing about axes extending heightwise of the shoe thus to operate them, and means for imparting wiper-operating movements simultaneously to all said arms.

13. In a lasting machine, wipers movable to wipe the margin of an upper inwardly over an insole at the opposite sides of the forepart of a shoe beyond its toe portion, a pair of arms supporting said wipers and mounted to swing each about an axis extending heightwise of the shoe thus to operate the wipers, additional wipers movable inwardly over the shoe bottom in different directions than said first-named wipers with components of movement toward the toe end of the shoe to wipe the margin of the upper over the insole in locations where the edge of the shoe bottom curves inward heelwardly of the ball line, a pair of arms supporting said additional wipers and mounted to swing about axes extending heightwise of the shoe thus to operate them, and means for operating one of said pairs of arms by the movements of the other pair of arms.

14. In a lasting machine, wipers movable to wipe the margin of an upper inwardly over an insole at the opposite sides of the forepart of a shoe beyond its toe portion, arms supporting said wipers and mounted to swing each about an axis extending heightwise of the shoe thus to operate the wipers, power-operated means for operating said arms, additional wipers movable inwardly over the shoe bottom in different directions than said first-named wipers with components of movement toward the toe end of the shoe to wipe the margin of the upper over the insole in locations where the edge of the shoe bottom curves inward heelwardly of the ball line, arms supporting said additional wipers and mounted to swing about axes extending heightwise of the shoe thus to operate them, and yieldable connections for operating said last-named arms by the movements of said first-named arms.

15. In a lasting machine, wipers movable to wipe the margin of an upper inwardly over an insole at the opposite sides of the forepart of a shoe beyond its toe portion, arms supporting said wipers and mounted to swing each about an axis extending heightwise of the shoe thus to operate the wipers, additional wipers movable inwardly over the shoe bottom in different directions than said first-named wipers with components of movement toward the toe end of the shoe to wipe the margin of the upper over the insole in locations where the edge of the shoe bottom curves inward heelwardly of the ball line, arms supporting said additional wipers and mounted to swing about axes extending heightwise of the shoe thus to operate them, yieldable means for operating said last-named arms by the movements of said first-named arms, and stops for limiting the operative movements of the arms supporting the additional wipers independently of the movements of said first-named arms.

16. In a lasting machine, wipers movable to wipe the margin of an upper inwardly over an insole at the opposite sides of the forepart of a shoe beyond its toe portion, arms supporting said wipers and mounted to swing about axes extending heightwise of the shoe and spaced apart widthwise of the shoe thus to operate the wipers, additional wipers for wiping the margin of the upper over the insole in locations where the edge

of the shoe bottom curves inward heelwardly of the ball line, arms supporting said additional wipers and mounted to swing about axes extending heightwise of the shoe in locations farther apart widthwise of the shoe than said first-named axes and in such relation to the shoe as to cause the additional wipers to have components of movement lengthwise of the shoe toward the toe end thereof relatively to the first-named wipers, and means common to all said arms for operating them.

17. In a lasting machine, wipers movable to wipe the margin of an upper inwardly over an insole at the opposite sides of the ball portion of a shoe, supports for said wipers mounted to swing each about an axis extending heightwise of the shoe thus to operate the wipers, additional wipers movable inwardly between the shoe and the wiping faces of said first-named wipers with components of movement along said faces toward the toe end of the shoe to wipe the margin of the upper over the insole in locations where the edge of the shoe bottom curves inward heelwardly of the ball line, and supports for said additional wipers mounted to swing about axes extending heightwise of the shoe thus to operate the additional wipers.

18. In a lasting machine, wipers movable to wipe the margin of an upper inwardly over an insole at the opposite sides of the ball portion of a shoe, arms supporting said wipers and mounted to swing each about an axis extending heightwise of the shoe thus to operate the wipers, additional wipers movable inwardly between the shoe and the wiping faces of said first-named wipers with components of movement along said faces toward the toe end of the shoe to wipe the margin of the upper over the insole in locations where the edge of the shoe bottom curves inward heelwardly of the ball line, arms supporting said additional wipers and mounted to swing about axes extending heightwise of the shoe thus to operate them, and means for operating said last-named arms by the movements of said first-named arms.

19. In a lasting machine, wipers movable to wipe the margin of an upper inwardly over an insole at the opposite sides of the ball portion of a shoe, additional wipers movable inwardly between the shoe and the wiping faces of said first-named wipers with components of movement along said faces toward the toe end of the shoe to wipe the margin of the upper over the insole in locations where the edge of the shoe bottom curves inward heelwardly of the ball line, and means for increasing the pressure of the wipers on the margin of the upper heightwise of the shoe when they are over the shoe bottom, all said wipers being resiliently flexible heightwise of the shoe to permit them better to conform to the contour of the bottom of the shoe when the pressure is thus increased.

20. In a lasting machine, wipers movable to wipe the margin of an upper inwardly over an insole at the opposite sides of the ball portion of a shoe, additional wipers movable inwardly in contact with the wiping faces of said first-named wipers with components of movement along said faces toward the toe end of the shoe to wipe the margin of the upper over the insole in locations where the edge of the shoe bottom curves inward heelwardly of the ball line, and means for heating said first-named wipers, the additional wipers being arranged to be heated by their contact with the first-named wipers.

21. In a lasting machine, wipers movable to wipe the margin of an upper inwardly over an insole at the opposite sides of the ball portion of a shoe, additional wipers movable inwardly in contact with the wiping faces of said first-named wipers with components of movement along said faces toward the toe end of the shoe to wipe the margin of the upper over the insole in locations where the edge of the shoe bottom curves inward heelwardly of the ball line, and retarders arranged to cooperate respectively with said first-named wipers and with said additional wipers to control the margin of the upper.

22. In a lasting machine, wipers movable to wipe the margin of an upper inwardly over an insole at the opposite sides of the ball portion of a shoe, additional wipers movable inwardly in contact with the wiping faces of said first-named wipers with components of movement along said faces toward the toe end of the shoe to wipe the margin of the upper over the insole in locations where the edge of the shoe bottom curves inward heelwardly of the ball line, retarders associated respectively with said first-named wipers and with said additional wipers for clamping the margin of the upper against the edges of the wipers substantially at the beginning of the wiping action of the wipers on the upper, and means for moving the retarders thereafter outwardly over the wipers in the course of the wiping operation.

23. In a lasting machine, wipers movable to wipe the margin of an upper inwardly over an insole at the opposite sides of the ball portion of a shoe, retarders for pressing the margin of the upper against said wipers to control the upper, means for moving said retarders outwardly over the insole toward the wipers, additional wipers movable inwardly over the shoe bottom in different directions than said first-named wipers with components of movement toward the toe end of the shoe to wipe the margin of the upper over the insole in locations where the edge of the shoe bottom curves inward heelwardly of the ball line, other retarders for pressing the margin of the upper against said additional wipers, and means for moving said other retarders outwardly over the insole in different directions than said first-named retarders with components of movement away from the toe end of the shoe.

24. In a lasting machine, wipers movable to wipe the margin of an upper inwardly over an insole at the opposite sides of the ball portion of a shoe, retarders for pressing the margin of the upper against said wipers to control the upper, arms mounted to swing each about an axis extending heightwise of the shoe to carry said retarders outwardly over the insole toward the wipers, additional wipers movable inwardly over the shoe bottom in different directions than said first-named wipers with components of movement toward the toe end of the shoe to wipe the margin of the upper over the insole in locations where the edge of the shoe bottom curves inward heelwardly of the ball line, other retarders for pressing the margin of the upper against said additional wipers, and other arms mounted to swing about axes extending heightwise of the shoe to carry said other retarders outwardly over the insole in different directions than said first-named retarders with components of movement away from the toe end of the shoe.

25. In a lasting machine, wipers movable to wipe the margin of an upper inwardly over an insole at the opposite sides of the ball portion of a shoe, retarders for pressing the margin of the

upper against said wipers to control the upper, supports for said retarders mounted to swing about axes extending heightwise of the shoe and spaced apart widthwise of the shoe, additional wipers movable inwardly over the shoe bottom in different directions than said first-named wipers with components of movement toward the toe end of the shoe to wipe the margin of the upper over the insole in locations where the edge of the shoe bottom curves inward heelwardly of the ball line, other retarders for pressing the margin of the upper against said additional wipers, and supports for said other retarders mounted to swing about axes extending heightwise of the shoe and spaced farther apart widthwise of the shoe than the axes of said first-named supports.

26. In a lasting machine, wipers movable to wipe the margin of an upper inwardly over an insole at the opposite sides of the ball portion of a shoe, retarders movable outwardly over the insole into positions to press the margin of the upper against said wipers to control the upper, additional wipers movable inwardly over the shoe bottom in different directions than said first-named wipers with components of movement toward the toe end of the shoe to wipe the margin of the upper over the insole in locations where the edge of the shoe bottom curves inward heelwardly of the ball line, other retarders movable outwardly over the insole in different directions than said first-named retarders with components of movement away from the toe end of the shoe into positions to press the margin of the upper against said additional wipers, members movable widthwise of the shoe to move said first-named retarders outwardly, and means for moving said other retarders also outwardly by the movements of said members.

27. In a lasting machine, wipers movable to wipe the margin of an upper inwardly over an insole at the opposite sides of the ball portion of a shoe, retarders movable outwardly over the insole into positions to press the margin of the upper against said wipers, additional wipers movable inwardly over the shoe bottom in differ-

ent directions than said first-named wipers with components of movement toward the toe end of the shoe to wipe the margin of the upper over the insole in locations where the edge of the shoe bottom curves inward heelwardly of the ball line, other retarders for pressing the margin of the upper against said additional wipers, arms mounted to swing each about an axis extending heightwise of the shoe to move said first-named retarders outwardly over the insole, other arms mounted to swing about axes extending heightwise of the shoe to carry said other retarders outwardly over the insole in different directions than said first-named retarders, and means for thus moving said other arms by the movements of said first-named arms.

28. In a lasting machine, wipers movable to wipe the margin of an upper inwardly over an insole at the opposite sides of the ball portion of a shoe, retarders movable outwardly over the insole into positions to press the margin of the upper against said wipers to control the upper and further movable thereafter outwardly over the wipers in the course of the wiping operation, additional wipers movable inwardly over the shoe bottom in different directions than said first-named wipers with components of movement toward the toe end of the shoe to wipe the margin of the upper over the insole in locations where the edge of the shoe bottom curves inward heelwardly of the ball line, other retarders movable outwardly over the insole in different directions than said first-named retarders into positions to press the margin of the upper against said additional wipers and further movable outwardly over said wipers in the course of the wiping operation, members movable widthwise of the shoe to move said first-named retarders outwardly, yieldable means for moving said other retarders outwardly by the movements of said members, and stop mechanism for limiting the outward movements of said other retarders independently of the movements of said first-named retarders.

BERNHARDT JORGENSEN.
